UNITED STATES PATENT OFFICE.

EDWARD COURT, OF MILWAUKEE, WISCONSIN, ASSIGNOR OF ONE-HALF TO MARTIN J. FISCHBACH, OF MILWAUKEE, WISCONSIN.

BOTTLE-TRAY.

1,023,925.

Specification of Letters Patent. Patented Apr. 23, 1912.

Application filed November 6, 1911. Serial No. 658,742.

To all whom it may concern:

Be it known that I, EDWARD COURT, a citizen of the United States, and resident of Milwaukee, in the county of Milwaukee and 5 State of Wisconsin, have invented certain new and useful Improvements in Bottle-Trays; and I do hereby declare that the following is a full, clear, and exact description thereof.

10 My invention refers to bottle-cleaning apparatus, its general object being to provide an illuminated dumping tray for the reception of a series of bottles preparatory to their delivery into the racks of a soaker or 15 washing machine, whereby the bottles are interposed between the vision of the operator and the light thereunder to thus render the said bottles transparent for inspection in order that any insoluble matter contained 20 therein may be detected, in which case the bottle or bottles containing such matter are culled and the full quota of the tray completed by substituting others.

Specific objects of my invention are to 25 provide a hollow box-like tray having a transversely fluted top, the indentures of which are apertured to form bottle seats; to provide a series of illuminating lamps within the hollow tray under the convexed 30 surfaces of the fluted top whereby said lamps in the form of electric bulbs are protected; to provide trunnion suspension means for the tray in juxtaposition to a bottle washing machine with which said 35 tray co-operates, and to provide automatic time-controlled means for tilting the tray after the series of bottles are inspected, whereby they are discharged into the washer bottle racks incidental to the same 40 being successively brought into alinement with said hollow bottle tray.

With the above and other minor objects in view the invention consists in what is herein shown, described and claimed.

45 In the drawings Figure 1 represents a sectional plan view of a bottle-tray embodying the features of my invention attached to a standard washing machine, with parts broken away to more clearly show certain 50 structural features, the section being indicated by line 1-1 of Fig. 2; Fig. 2, a detailed longitudinal sectional view of the tray, the section being indicated by line 2-2 of Fig. 1; Fig. 3, a cross-section of the 55 same as indicated by line 3-3 of Fig. 1;

Fig. 4, an end view of said tray showing the trunnion suspension means for the tray in connection with a washer, and Fig. 5, a general sectional elevation of a portion of a washing machine having attached thereto 60 a hollow tray embodying the features of my invention, the view illustrating automatic means in connection with the washing machine for tilting said tray.

Referring by characters to the drawings, 1 indicates a boxlike tray body having an open side that is provided with a hinged gate 2, whereby access may be had thereto, the gate being closed by a thumb-nut 3 that is in threaded engagement with an aperture formed in a longitudinally disposed angle-iron rail 4, which rail is secured to the end walls 1 of the tray body and constitutes an abutment bottle-rest. The body portion 1 of the tray is closed by a transversely fluted top-plate 5 which is secured to inturned flanges of the vertical tray walls and is provided with slotted apertures 5' that extend from an intermediate point to the lower edge of 80 the top, which apertures are located within the concavities of the fluted plate, said concavities in conjunction with the apertures forming seats for the bottles. By the above arrangement of fluted top it will be apparent that when a number of bottles corresponding to the capacity of the tray are laid thereon they can be quickly distributed so as to automatically seat within the bottle rests and when so seated, form closures for 90 the various sight apertures.

A series of lamps in the form of electric bulbs 7 are attached to a keeper bar 8, which bar is inserted within the tray upon the hollow bottom through the gate 2 and secured to said bottom by suitable retaining screws 9, the keeper bar being disposed longitudinally of the tray with the bulbs 7 so spaced that they are positioned between the bottle seats of the top and rest within 100 its fluted concavities whereby said bulbs are protected.

Secured to the end walls of the tray are trunnion blocks 9', the same being preferably hollow for the purpose of admitting 105 conductor wires 10 for the supply of electric current to the series of lamp bulbs. There being no movement upon the axis, it is apparent that the wires so disposed will not be subjected to constant twisting strain. 110

2
The tray trunnions are journaled in apertured hubs 11 of brackets 12, webs of the same being adjustably secured to angle-iron struts 13, that, as shown, constitute members of the supporting frames of a soaker or washing machine as best shown in Fig. 5. The said figure illustrates the tray in connection with parallel endless conveyer chains A that are guided in the angle-iron struts 13 and connected at regular intervals by bottle racks B, the said racks being arranged to travel past the inner edge of the tray which is adapted to be tilted and the bottles contained thereon discharged by gravity into a rack that is so timed to be alined with the tray incidental to the tilting movement thereof.

The conveyer chains A are arranged to travel over sprocket-wheels C that are mounted upon a shaft D which structure forms no part of my invention and is that ordinarily employed in bottle washers or soakers.

The tray tilting mechanism comprises a gravity-controlled lever 14 which is fulcrumed above the sprocket wheel C and is provided with an anti-friction roller for engagement with a cam-wheel 15 that is mounted upon the conveyer shaft. The free end of this lever is connected to one end of a rod 17, its opposite end being passed through an aperture ear 18 that projects from one end-wall of the tray. Interposed between the projecting tray ear and an adjustable nut 19 carried by the rod, is a coiled spring 20, the function of which is to permit a yielding connection between said rod and tray, whereby overthrow of the cam actuating lever is provided for incidental to limited downward movement of the tray, whereby the angle of discharge is fixed. The angle of discharge of the tray is limited by an adjustable bolt 21, which bolt is in threaded union with a stud 22 that extends from one of the brackets, the bolt being adapted to engage the bottom face of the tray when the latter is tilted to its discharging position.

From the foregoing description it is apparent that after a series of bottles have been properly located upon the tray and inspected and culled, the time-controlled tilting mechanism connected thereto will be actuated by the cam-wheel to cause a tilt of the tray, when one of the racks C is in the proper position to receive the series of bottles, which are discharged therein, the tray being thereafter returned to its normal receiving angle preparatory to the distribution thereon of another series of bot-

ties for inspection, which series will be discharged into the succeeding bottle washer rack, it being understood that the travel of the conveyer chain is at such speed as to permit ample time for inspection during the interval required for one rack to travel to the position of the succeeding rack. 65

I claim:

1. In a bottle washing machine having supporting struts, a shaft mounted thereon, sprocket-wheels carried by the shaft, endless conveyer chains mounted upon the sprocket-wheels, and bottle racks carried thereby; the combination of a tiltable hollow receiving tray, a transversely apertured top closure for said tray, illuminating means located under the tray top, and tilting mechanism in connection with the tray under control of the washing machine. 75

2. A tray comprising a hollow body, a top therefor provided with a series of transversely disposed apertures constituting bottle seats, illuminating means located within the tray body, supporting trunnions associated with the tray ends, and means for 85 tilting the tray.

3. A tray comprising a hollow body, a transversely fluted top therefor having apertures within the fluted indentures to constitute bottle seats, and illuminating means 90 located within the tray body.

4. A tray comprising a hollow body, a transversely fluted top therefor having apertures within the fluted indentures to constitute bottle seats, illuminating means located within the tray body, supporting trunnions for the tray, and tilting mechanism 95 for controlling the angular position of said tray.

5. In a bottle washing machine having supporting struts, a shaft mounted thereon, sprocket-wheels carried by the shaft, endless conveyer chains mounted upon the sprocket-wheels, and bottle racks carried thereby; the combination of a hollow receiving tray, trunnions extending from the tray, means for supporting the trunnions, a transversely apertured top closure for said tray, illuminating means located under the tray top, and tilting mechanism in connection with the tray under control of the washing machine. 105

In testimony that I claim the foregoing I have hereunto set my hand at Milwaukee in the county of Milwaukee and State of Wisconsin in the presence of two witnesses. 115

EDWARD COURT.
